UNITED STATES PATENT OFFICE

HENRY JACOBSON AND KARL AICHELEN, OF MILWAUKEE, WISCONSIN

LOCKING DEVICE FOR DOORS OF BALING PRESSES

Application filed April 12, 1928. Serial No. 269,375.

The invention relates to baling presses and more particularly to a device for locking the doors thereof.

With the usual devices for locking the doors of baling presses the lock secures the doors in closed position but when released the doors are free to fly open under the pressure created by the resiliency of the compacted bale and this presents a dangerous situation for the operator, who may be seriously injured if struck by one of the doors. The object of our invention is to prevent a liability of injury as above recited by providing a door-locking mechanism which in addition to holding the doors securely locked during the compression of the bale will also permit a gradual and positively controlled opening of the doors so that the locks will not be released until the natural re-expansion of the bale has spent itself.

The invention further consists in the several features hereinafter set forth and more particularly defined by claims at the conclusion hereof.

25 In the drawings Fig. 1 is a side elevation view of a baling press equipped with a locking device embodying the invention, parts being broken away;

30 Fig. 2 is a front elevational view of the press, parts being broken away;

Fig. 3 is a section taken on the line 3—3 of Fig. 1;

35 Fig. 4 is an enlarged side elevational view of the press box, parts being shown in section;

Fig. 5 is a detail sectional view taken on the line 5—5 of Fig. 3.

The locking device has been shown in connection with one form of baling press, such as 40 is used for baling scrap paper, in which the numeral 6 designates the press box, 7 the pressing ram, 8 the movable top cover, and 9 the doors of the press box. The ram 7 is here shown as hydraulically operated and 45 the box extends to a position above the floor 10, the cover 8 being mounted on a carriage 11 provided with wheels 12 movable on rails 13, the cover being moved to one side, as shown in Fig. 2, during the charging of the 50 box and then moved over the top of the box

and held in this position in known manner during the pressing operation.

The doors 9 of the press box are here shown as forming three sides of that portion of the box that holds the completed bale but it will be understood that the locking device hereinafter described may be used on other door arrangements. As shown, these doors are hinged to the rear side of the press box on vertically disposed hinge pintles 14 and are provided with lock-engaging lugs 15.

The locking mechanism includes a pair of locking members 16 and means under the control of the operator for moving said members to locking or releasing position, said means holding said members in any intermediate position. These members are shown as a pair of oppositely disposed bell crank levers having spaced arms 17 engageable with the lugs 15 of the adjacent door and a medially disposed arm 18, each of said levers being mounted on a pivot shaft 19 carried in a frame member 20 secured to the supporting frame 21 of the press box.

70 The arm 18 of each lever is connected by a pivot bolt 22 and a pair of toggle links 23 to bolt or pivot projections 24 formed on a collar 25 in which a threaded nut 26 is mounted. An operator - controlled, lock - operating, threaded shaft 27 is journaled at one end in a bearing 28 in the frame member 20 and in a bearing 29 in the arms 30 of said frame with a thrust collar 31 associated with said bearing, the extended end 32 of said shaft having a handwheel 33 securely fastened thereto for the purpose of turning said shaft.

75 With this construction the doors are closed and locked before charging, the turning of the shaft 27 in a clockwise direction serving to move the nut 26 toward the box and thus, through the links 23, swinging the levers 16 inwardly against the lugs 15 to hold the doors closed. After the bale has been compressed the turning of the shaft 27 in the opposite direction gradually swings the levers 16 outwardly toward the dotted line position shown in Fig. 3 and this turning may be done intermittently so that the re-expansion of the bale, as the doors are opened, may spend itself before the locking members are actually re-

leased from the doors, since the travel of the doors relative to said locking member or lever permits said member to remain in controlled engagement with the doors for a considerable part of their opening movement. Thus, as the doors are at all times, even though in a partially open position, locked against free movement any danger of injury to the operator from a free movement of the 10 door, under the action of the expanding bale, is prevented.

We desire it to be understood that this invention is not to be limited to any specific form or arrangement of parts except insofar 15 as such limitations are specified in the claims.

What we claim as our invention is:

1. In a baling press, the combination with a press box having a pair of movable doors, of locking mechanism for said doors comprising a pair of locking members engageable with said doors, and self-locking means independent of said doors for positively actuating said locking members whereby to hold said doors closed and to restrain the free 25 opening movement of said doors during their opening movement.

2. In a bailing press, the combination with a press box having a pair of pivoted doors forming the sides and one end of the delivery 30 end of said press box, of a pair of locking levers engageable with said doors, a screw shaft, a nut, means operatively connecting said nut with said levers to swing said levers on the movement of said nut upon said shaft, and means, under the control of the operator, 35 for turning said shaft.

3: In a bailing press, the combination with a press box having a pair of pivoted doors forming the sides and one end of the delivery 40 end of said press box, of a pair of locking levers engageable with said doors, a screw shaft, a nut mounted on said shaft, means including toggle links operatively connecting said nut with said levers, and means under 45 the control of the operator for turning said shaft.

4. In a bailing press, the combination with a press box having a pair of pivoted doors forming the sides and one end of the delivery 50 end of said press box, of a pair of bell crank levers, each having spaced arms engageable with the adjacent door and a centrally disposed arm, a screw shaft, means including links operatively connecting said centrally 55 disposed arms to said shaft, and means for turning said shaft.

5. In a bailing press, the combination with a press box having a pair of pivoted doors forming the sides and one end of the delivery 60 end of said press box, locking mechanism for said doors comprising a pair of pivoted levers engageable with adjacent parts of the doors, and means for positively moving said locking levers to secure the doors in closed 65 position and to maintain said levers in oper-

ative engagement with said doors on the opening movement of said doors to prevent their free opening movement under the expansive action of the bale.

In testimony whereof, we affix our signatures.

HENRY JACOBSON.
KARL AJCHELEN.
